FLEXIBLE KEY FORM FOR FORMING RECESSES IN CONCRETE STRUCTURES

Robert Maxwell James, Buffalo, N. Y.

Application March 29, 1949, Serial No. 84,062

13 Claims. (Cl. 25—118)

1

This invention relates to a flexible tool device suitable for use in construction work in connection with the formation of undercut niches or keys in concrete walls and forms. As such, this invention relates generally to mold apparatus used in connection with the formation of plastic block material. More particularly, this invention relates to a flexible key form suitable for use on mold linings employed in the formation of concrete conglomerates which are to be adapted to perform various engineering and architectural functions.

As is well known to those versed in the art, concrete and other plastic building material may be adapted to an infinite variety of uses in architecture and engineering including massive structures such as heavy foundations, retaining walls, dock walls, break waters, bridges and dams and more intricate constructions in ferro-plastic for floors, columns, buildings, arches, domes, towers, water tanks, pontoons, foundation cylinders, tiles, open-work jetties, and many other purposes.

Concrete as a building material is distinguished by the facility with which it can be deposited and molded while in a plastic condition into almost any desired shape.

It is usually necessary, therefore, to provide suitable mold forms for receiving the plastic concrete aggregate thereagainst, and these molds are, of course, constructed to define any desired molding pattern.

Heretofore, construction workers have experienced many difficulties. Plain or mass concrete is not readily adaptable to architectural treatment, yet it can be used wherever massive masonry or brick work is suitable. Thus, the concrete mold forms provided for the use of the building tradesmen in the past have usually consisted largely of simple box-like forms held together by metal straps or the like.

A hardened concrete form resulting from casting a plastic concrete aggregate in such a mold defines a uniformly flat surface which must of necessity be augmented or adapted for the use of special anchoring devices if it is to be employed as a foundation for plaster, acoustic tile, marble or slate slabs, or other types of finishing material as may be desired in various types of building construction.

The present invention contemplates the provision of flexible key forms made of a molded resilient material such as hard rubber or the like, which may be affixed to the liner surface of mold forms, whereby concrete forms having unique structural advantages may be produced.

2

Each of the key forms constructed in accordance with my invention is shaped in the form of a substantially circular disk and is provided with a plurality of radially extending grooves on one face thereof. A circumferential, angularly inclined lip is formed on the other face which terminates in an annular recessed hinge area. A circular suction cup portion integrally formed in the disk and lying in concentric relationship with the lip portion is also provided.

A plurality of key forms having these characteristics may be selectively positioned to project outwardly upon the liner surface of a mold form and may be held thereupon by normal atmospheric air pressure.

A mold form equipped with key forms having the aforementioned characteristics receives the plastic concrete aggregate in surrounding molded proximity with the projecting key forms, thereby shaping the surface of the ultimate hardened concrete form to conform to the pattern defined by the mold liner surface.

By pulling the mold form away from the hardened concrete form, the flexible key forms carried thereby may be easily withdrawn from the concrete, thereby producing a plurality of unique dovetailed niches or undercuts in the concrete surface which may be utilized for various and sundry purposes. Easy removal of the key forms is facilitated by the unique features incorporated in the key forms whereby a hinging action occurs which permits the forms to contract radially through the areas defined by the radial grooves.

An object of this invention is to provide a flexible key form suitable for attachment to the liner face of mold forms without the use of separate fastening means, whereby niched surfaces may be produced in a hardened plastic conglomerate.

Another object of this invention is to provide an improved mold form equipped with flexible key forms suitable for supporting metal reinforcing members during the casting of ferro-concrete structures without the necessity of employing additional "chairs."

A further object of this invention is to provide a flexible key form for use with rigid mold forms which expedites the formation of improved concrete forms economically and with great facility.

Many other advantages and objects of the instant invention will be evident to those versed in the art upon making reference to the following detailed description and the accompanying drawings, in which:

Figure 1 is a partial elevational view showing

3

the liner surface of a mold form constructed in accordance with a method contemplated by this invention;

Figure 2 is a cross-sectional view partly broken away showing a key form as provided in the instant invention affixed to a liner surface of a mold form;

Figure 3 is a plan view of a key form constructed in accordance with the principles of my invention;

Figure 4 is a cross-sectional view taken on a diametric axis of the key form shown in Figure 3 and shows the details of construction and arrangements of parts of the key form prior to attachment to a liner surface of a mold form;

Figure 5 is a bottom view of the key form shown in Figure 3;

Figure 6 is a partial cross-sectional view showing a key form attached to the liner surface of a mold form and surrounded by a plastic aggregate such as concrete or the like;

Figure 7 is a partial cross-sectional view showing how the key forms illustrated in Figure 6 may be removed from the concrete conglomerate after hardening;

Figure 8 is a partial cross-sectional view showing the details of the undercut niche or recess resulting in the hardened conglomerate after the removal of the key form shown in Figures 6 and 7;

Figure 9 is a partial cross-sectional view showing an alternative method of fastening the key form of the present invention to the liner surface of a mold form.

As shown on the drawings:

Referring first to Figures 3, 4 and 5, a key form is indicated generally at 10. Each key form 10 comprises a substantially circular disk made of a flexible material. It is highly desirable that the material of which the disks are made have comparatively rigid characteristics and, to that end, each of the key forms 10 may be preferably formed of molded oil-resistant rubber such as neoprene or the like.

A plurality of V-shaped grooves 11 are formed in the upper face and on the outer peripheral portion of the form 10 in spaced radial relationship to one another. The apices of the V-shaped grooves 11 lie substantially on a common circular axis concentric with the outer periphery of the form 10, but lying on an inner portion toward the center of the form 10.

The upper surface of the form 10 may also be dished out to form a slight circular recess as at 12.

It will be noted that due to the provision of the radially spaced V-shaped grooves 11, the upper surface of the key form 10 is characterized by a plurality of projecting tongue portions 13 which are likewise radially spaced in relation to one another. Thus, as may be seen in Figure 3, the plan view of the key form 10 resembles a rosettelike configuration.

The tongue portions 13 are provided with suitably rounded corners and are adapted to be angularly inclined in such a manner as to taper inwardly toward the under portion of the key form 10. The form 10 therefore takes the configuration of a substantially circular disk skived along its peripheral edge as at 14 to form a truncated conical segment.

As may be seen in greater detail on Figures 4 and 5, the inclined portions 14 of the tongues 13 terminate in a circular lip 15 of smaller diameter than the outer diameter of the key form 10.

4

The lip 15 is angularly inclined and extends inwardly toward the center of the key form 10 in such a manner as to substantially define the surface configuration of a cone.

The lip 15 terminates in an inwardly disposed annular recess or hinge area 16 (Figure 4). A central hub or suction cup 17 is formed in such a manner as to extend away from the annular recess or hinge area 16 and lie in concentric relationship with the lip 15. The lip of the hub or suction cup 17 is circular in form and surrounds a depressed cup portion 18.

It will be noted that the plane developed by the circular lip of suction cup 17 normally lies slightly below the plane developed by the circular lip 15 at its outermost extremities.

Referring now to Figure 2, a key form 10 is shown applied to the liner surface of a typical rigid mold form 19. When a form 10 is first positioned on the liner surface the lip 15 effectively contacts the liner surface and will yield against the resilience of the form 10 to produce a tight edge with the liner surface. This characteristic is highly desirable inasmuch as a strong niche lip may be formed in the concrete undercut in the locale between the mold form 19 and the key form 10. It will also be apparent that the snug relationship between the mold form 19 and the key form 10 operates to prevent concrete leakage into the suction cup area.

By firmly pressing the key form 10 onto the mold form 19, the inwardly disposed suction cup 17 is brought into contact with the liner surface and the air normally contained in the cavity of the recess 18 will be expelled.

It should be apparent that the suction cup 17 operates in a conventional manner to hold the key form 10 firmly in place upon the liner surface by virtue of the atmospheric air pressure exerted upon the outer surface of the suction cup 17 in the direction of the recess 18 and the mold form 19.

It will be noted that when the key form 10 is firmly affixed to the mold form 19, as shown in Figure 2, the upper surface of the key form 10, which normally describes a slightly arcuate configuration (Figure 4), assumes a substantially planar surface parallel to the liner surface. Because of these characteristics, a plurality of key forms affixed to a liner surface of a mold form presents a uniform planar surface spaced a predetermined distance from the liner surface corresponding to the thickness of the key forms in such a manner as to present an effective supporting means for reinforcing metals used in ferroconcrete structures. It will be apparent that reinforcing metal may be laid across the various key forms and the plastic concrete aggregate may subsequently be molded around such reinforcement without the employment of additional supporting "chairs" as have been required heretofore.

Referring now to Figure 6, the key form 10 is shown affixed to the mold form 19 and surrounded by a plastic aggregate 20, such as concrete or the like. It will be noted that the suction cup area interiorly of the lip 15 is free of concrete leakage despite the molded proximity of the plastic aggregate 20 to the liner surface of the mold form 19 at the locale of the key form 10.

Referring now to Figure 7, the mold form 19 is shown in the process of removal from the plastic aggregate which, it is assumed, has hardened into a conglomerate 20a such as a concrete form. The annular recess 16 forms a hinge area which provides for the necessary flexibility

to permit removal of the key form with great facility. Thus, it will be evident that the various tongue portions 13 pivotally hinge about the recess or hinge area 16 and simultaneously contract radially through the areas provided by the V-shaped grooves 11 as the key form 10 is withdrawn. The suction cup 17, of course, remains firmly affixed to the liner surface of the mold form 19.

Referring now to Figure 8, it will be evident that upon the removal of the key form 19 from the hardened plastic conglomerate 20a, an undercut niche or key 21 will be left in the surface of the conglomerate 20a corresponding to the projecting configuration defined by each key form 10 upon the liner surface of the mold form 19.

The niches 21 leave a wall face on the conglomerate 20a which is smooth and without projecting interferences and which is characterized by one or more dovetailed recesses 22 shaped to correspond to the tongues 13 of the form 10 and a plurality of radial fins 23 which correspond to the shape of the V-shaped grooves 11 in the key form 10. The radial fins 23 effectively reinforce the lip of each niche 21 and add considerably to the anchorage strength potential available in the use of such a dovetailed recess.

Each niche or key 21 may be used for a variety of purposes. For example, the niches could be filled with plastic wood or a similar nail-holding material to provide positive anchorage for plaster grounds. A niche adapted in such a manner would also furnish a positive method of supporting acoustical tile.

By employing a supplementary anchor device shaped to conform to the configuration of the niche 21, the niche could be filled with mortar or plaster of Paris after the anchor devices are inserted therein, and such devices could be used for anchoring marble, slate, or other slab-like finishing material.

As may be seen on Figure 1, a liner surface of a mold form is shown having a plurality of key forms 10 mounted thereon. Because of the pleasing configuration defined by the rosette-like appearance of the plurality of corresponding niches or keys 21, a pleasing ornamental effect may be imparted to a concrete surface or the like. It will be apparent that such a surface lends itself to suitable decorative effects as may be achieved, for example, by the supplementary use of various colored pigments and paints.

Although I have shown and described the instant key forms 10 as being attached to the liner surface of a mold form 19 by the use of a suction cup 17 and without the use of additional adhesives or plastic means, it will be apparent to those versed in the art that the instant key form 10 is readily adaptable to the use of supplementary fastening material such as adhesives or the like for the purpose of effecting a permanent bond between each key form 10 and the liner surface on a mold form 19.

By way of illustration, therefore, Figure 9 shows a mold form 19 to which is affixed a key form 10. A suitable adhesive 25 is shown as being placed on the lip of the suction cup 17. Thus, the key form 10 is firmly bonded to the liner surface of the mold form 19.

It will be apparent to those versed in the art that I have described a method of constructing concrete forms and mold forms whereby a concrete surface may be produced which is characterized by highly useful and decorative undercut niches or keys which may be used for anchorage

of plaster, acoustic tile, or finishing material such as marble and slate.

It will also be apparent to those versed in the art that I have described a new and improved key form device suitable for attachment to the liner surface of mold forms and adapted to produce useful and decorative undercut niches or keys in hardened concrete surfaces.

Although I have resorted to detail in the description of my invention for the sake of clarity, it is contemplated that many modifications may be suggested by those skilled in the art without departing from the essential spirit of my invention. I do not wish to be limited, therefore, by the specific embodiments herein shown by way of illustration.

I claim as my invention:

1. A flexible key form defining a disk having a plurality of spaced radial tongues and grooves on one face thereof, a circular lip of smaller diameter on the other face thereof and an integral suction cup portion interiorly of said lip portion, said key form defining a recessed hinge area in the locale between said lip and suction cup portions.

2. A flexible key form defining a disk, said disk comprising an integral construction having a plurality of radially spaced tongues and grooves on one face thereof, a central hub defining a suction cup on the other face thereof, an annular recess surrounding said hub, and an angularly inclined lip portion extending outwardly away from said recess.

3. A flexible key form substantially in the form of a disk, said disk comprising an integral construction having a plurality of spaced grooves on one face thereof, the portions of said disk between said grooves defining a skived peripheral edge, a circular lip on the other face of said disk lying substantially at the base of said skived peripheral edge, a recessed portion interiorly of said lip and on said other face, a central hub defining a suction cup extending into said recessed portion, and an annular recessed hinge area at the base of said hub.

4. A flexible key form substantially in the form of a disk, said disk defining in an integral construction a plurality of spaced grooves on one face thereof, a skived peripheral edge along the portions of said disk between said grooves, a circular lip on the other face thereof lying substantially at the base of said skived peripheral edge, a recessed portion interiorly of said lip and on said other face, a central hub forming a suction cup extending into said recessed portion but terminating short of the plane developed by said lip, and an annular recessed hinge area at the base of said hub.

5. A flexible key form for use with a rigid mold form defining a flat liner surface, comprising, a disk having a plurality of spaced radial tongues and grooves on one face thereof, a circular lip of smaller diameter on the other face thereof and an integral suction cup formed interiorly of said lip portion, said key form further defining a recessed hinge area in the locale between said lip and suction cup portions.

6. A flexible key form for use with a rigid mold form defining a flat liner surface, comprising, a disk, said disk comprising an integral construction having a plurality of radially spaced tongues and grooves on one face thereof, a central hub defining a suction cup on the other face thereof, an annular recess surrounding said

hub, and an angularly inclined lip portion extending outwardly away from said recess.

7. A flexible key form for use with a rigid mold form defining a flat liner surface comprising a disk-like form, said disk defining in an integral construction a plurality of spaced grooves on one face thereof, a skived peripheral edge along the portions of said disk between said grooves, a circular lip on the other face thereof lying substantially at the base of said skived peripheral edge, a recessed portion interiorly of said lip and on said other face, a central hub defining a suction cup extending into said recessed portion, and an annular recessed hinge area at the base of said hub.

8. A flexible key form for use with a rigid mold form defining a flat liner surface and shaped substantially in the form of a disk, said disk comprising in an integral construction an upper face defining a plurality of spaced grooves, the portions of said disk between said grooves defining a skived peripheral edge, a circular lip on the other face thereof lying substantially at the base of said skived peripheral edge, a recess portion interiorly of said lip and on said other face, a central hub defining a suction cup extending into said recess portion but terminating short of the plane developed by said lip and an annular recessed hinged area at the base of said hub.

9. As an article of manufacture, a flexible key form made of rubber or the like, said form defining a substantially circular disk skived along its peripheral edge to form a truncated conical segment, said form further defining a plurality of V-shaped grooves arranged in spaced radial relationship to one another on one face of said disk, the apices of said grooves lying on a common circular axis on an inner portion of said form concentric with its periphery, said form including an angularly inclined conical lip on the opposite face of said form terminating in an inwardly disposed annular recess and a circular suction cup extending away from said annular recess, the lip of said suction cup terminating in substantial co-planar relation with the outermost portion of said lip, when said form is held on a flat surface by means of atmospheric air pressure, said key form being deformable within

the limits prescribed by the hinging action of said annular recess and the contraction action of said V-shaped grooves.

10. A flexible key member for the liner surface of a mold form and adapted to shape a dovetail recess in a mass of plastic aggregate hardened in the mold form and comprising a truncated conical body portion, a flexible lip on the body portion adapted to engage the liner surface of the mold form, said body portion having a recess interiorly of said lip, a hub forming a suction cup and extending into the recess, said suction cup terminating short of the plane normally developed by said lip, said body portion being made of a flexible material whereupon movement of said hub toward the liner surface of the mold form will flex said lip at the liner surface to form a curved recess, whereby the dove-tailed recesses formed in the plastic aggregate will have curved edge portions.

11. A flexible key member according to claim 10 in which the body portion is provided with a plurality of radially spaced tongues and grooves to promote radial contractibility of the key form and to form radially spaced reinforcing fins in the dovetailed recesses.

12. A flexible key member according to claim 10 in which a flexible hinge portion is situated between said hub and said body portion to permit flexure of the body portion about said hub upon withdrawal of the key member from the hardened plastic aggregate.

13. A key member according to claim 12 in which the body portion is provided with a plurality of radially spaced tongues and grooves to promote radial contractibility of the key member and to form reinforcing fins in the dove-tailed recesses.

ROBERT MAXWELL JAMES.
